UNITED STATES PATENT OFFICE.

FERDINAND F. SCHUPP, OF LOUISVILLE, KENTUCKY.

VENTILATOR.

1,204,702.

Specification of Letters Patent. Patented Nov. 14, 1916.

Application filed October 11, 1915. Serial No. 55,266.

To all whom it may concern:

Be it known that I, FERDINAND F. SCHUPP, a citizen of the United States, and resident of Louisville, in the county of Jefferson and State of Kentucky, have invented certain new and useful Improvements in Ventilators, of which the following is a specification.

This invention relates to certain improvements in ventilators, and the objects and nature of the invention will be readily understood by those skilled in the art in the light of the following explanation of the accompanying drawings illustrating what I now believe to be the preferred embodiment from among other formations and arrangements within the spirit and scope of my invention.

An object of the invention is to provide a device whereby ventilation is possible in all manner of weather without the entry of any foreign matter therein.

A further object of the invention is to provide a ventilator having means for varying the opening into the casing thereof.

A further object of the invention is to provide a ventilator elevating means for an adjustable ventilator whereby the adjustment is possible without materially changing the structure or design thereof.

A further object of the invention is to provide means for elevating or lowering the cover of a ventilator of a simple, efficient and practical type.

A further object of the invention is to provide means for preventing the entry of rain, snow and so forth, and still permit entry or departure of air to and from the ventilator when the cover thereof is in normal lowered position.

A still further object of the invention is to provide certain improvements in details of construction and arrangements and combinations for the production of a highly efficient and practical ventilator.

The invention consists in certain novel features in construction and in combinations and arrangements as more fully and particularly pointed out and specified hereinafter.

Referring to the accompanying drawings, Figure 1, is a vertical section. Fig. 2, is a horizontal section taken on the line *a—a*, Fig. 1. Fig. 3, is a horizontal section taken on the line *b—b*, Fig. 1.

In the particular example illustrated, I show the casing 1, having its upper edge outwardly and downwardly flared to form

the portion 2. Cross bars 3, are diametrically placed across the upper end of the casing 1. At their outer ends these cross bars 3, are shaped to conform with the portion 60 2, and fastened rigid therewith by any suitable means such as bolts or rivets 4, and are then turned upwardly to provide the vertical standards 5. A band or any appropriate means 6, is fastened to the standards 5. 65 This band or member 6, completely encompasses the top of the casing 1, and its function will be pointed out hereinafter.

Within the casing 1, and suitably fastened to the inside thereof, I provide the 70 guides or slotted members 7. These members 7, are placed directly beneath the cross bars 3, where they meet the edge of the casing. Hence, in the particular example illustrated, I provide four of these guides. Directly above the guides 7, and in alignment therewith, the cross bars 3, are likewise slotted to form guides. The purpose of these guides on the interior of the casing and in the cross bars will appear in the following 80 description.

Slidably mounted in the guides 7, and the slots of the cross bars 3, I show the rods 8. These rods in the specific example illustrated, are fastened to and made rigid with 85 a spider or other suitable supporting and bracing means 9, by means of nuts 10, working on threads provided on the ends of the rods 8. At their upper ends these rods 8, are provided with brackets or supports 11, 90 which are inclined downwardly from the horizontal at an angle approximately equal to the incline of the flared edge 2.

Any suitable cover such as 12, is provided and carried by the brackets 11. The edges 95 of the cover 12, project beyond the brackets 11, at a distance permitting the cover to be lowered below the horizontal plane of the top edge of the member 6.

Now, it is seen that I provide a frame 100 composed of the spider 9, and the cover 12, rigidly joined by the rods 8, and that this frame is adapted to be raised or lowered, guided by and sliding in the guides 7, and the slots in the cross bars 3. 105

Any suitable means may be provided for raising or lowering the top of my ventilator, but in the example illustrated, I disclose my preferred means for performing this operation. I will now describe this 110 means which is shown by Fig. 1, of the drawings.

At the intersection of the cross bars 3, by any suitable means such as 13, I fasten the pulley or block 14. This pulley 14, depends from the under side of the cross bars 3, 5 directly below their intersection. At the center of the spider 9, I form a hole or opening and to one side of this center opening, I provide an opening such as 15, having a narrow slot formed from one edge 10 thereof. A rope line, or any other suitable flexible member 16, having a ball 17, at one end and the balls 18, and 19, at suitable distances therefrom, is passed up through the central opening of the spider 9, over the 15 pulley 14, and down through the opening 15. The ball 17, prevents this member 16, from passing completely through the opening at the center of the spider. It is understood, of course, that these balls on the line 20 16, are fastened or formed rigid therewith. The ball 19, is passed down through the opening 15, and then moved under the narrow slot therefrom and this slot being smaller than the diameter of said ball prevents it from passing therethrough. Hence, 25 it is seen that by means of the balls 17 and 19, and the line 16, the frame which is slidably and loosely mounted in the aforementioned guiding means and carries at its upper end the cover 12, is held in normal 30 closed position, as shown by Fig. 1.

The operation of my device is as follows: The frame and cover being in the position shown in Fig. 1, it is desired to raise the 35 cover and increase the distance between it and the member 6, thus permitting more air to pass into or out of the casing 1. The lower depending end of the line 16, is pulled downwardly. Now this line working over 40 the pulley 14, when pulled in this manner, will exert an upward pull on the spider 9, through the medium of the ball 17, bearing against the under side thereof. As the spider 9, is pulled upwardly it will raise the 45 cover 12, which is rigid with the rods 8, which in turn are rigid with the spider and the entire structure will be guided and steadied in this movement by the guides 7, and the slots in the cross bars 3. The ball 50 18, will be placed at such a distance from the ball 19, that when the cover 12, has reached the desired height it will have passed through the opening 15, and may

then be placed under the slot therefrom where it will retain the sliding frame and 55 cover 12, in the desired position.

When it is desired to lower the cover, the reverse of the above operation is performed, with the exception that gravity will be the exerting force, and the line 16, passed upwardly until the ball 19, reaches the opening 15, where the movable structure may be retained in the proper position by this ball 19. In regard to these balls 18 and 19, they may be placed at any required distance so 60 as to increase or decrease the height to which cover 12, may be raised or to which it may be lowered. This adjustment, of course, depending on the requirements for the ventilator. A smaller adjustment of 65 this height can be made by means of the nuts 10, on the threaded ends of the rods 8.

With the hereinbefore described ventilator, it is possible to obtain ventilation at all times and in any weather. As will be 70 seen by the drawings when the cover is lowered a somewhat tortuous passage is formed for the air to enter, doing away with the possibility of rain, snow and so forth, entering in stormy weather. Thus 75 the casing is never closed and air may enter or leave at any and all times. The cover may be glass or solid and of any desired shape and the slopes of the flare 2, or of the brackets 11, may be changed. 80

What I claim is:

In a ventilator, the combination of a casing, a band of greater diameter than said casing fixed at the upper edge thereof and extending a distance above and below said 90 edge, with a vertically movable cover of greater diameter than said casing and of smaller diameter than said band, and adapted to lie in normal elevated position with its effective peripheral edge a distance 95 above the upper edge of said band and means for raising and lowering said cover and maintaining the same in normal elevated position.

In testimony whereof I affix my signature 100 in the presence of two witnesses.

FERDINAND F. SCHUPP.
